(57) **CLAIM**

The ornamental design for a head component for myofascial release device as shown.

DESCRIPTION

FIG. 1 is a rear, top, right side isometric perspective view of a head component for myofascial release device in accordance with our design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view shown at an enlarged scale thereof; and,

FIG. 7 is a bottom plan view shown at an enlarged scale thereof.
